MAX RECHER, OF BROWNS MILLS, NEW JERSEY, ASSIGNOR TO RECHER BROS. LTD., OF NEW YORK, N. Y., A CORPORATION OF NEW JERSEY.

NECKTIE-INTERLINING FABRIC.

Application filed September 12, 1925. Serial No. 56,087.

To all whom it may concern:

Be it known that I, MAX RECHER, a citizen of Switzerland, residing at Browns Mills, Burlington County, State of New Jersey, have invented certain new and useful Improvements in Necktie-Interlining Fabrics, of which the following is a specification.

This invention relates to fabrics and in particular to a type particularly woven and treated for use as necktie or other linings where a stretchiness of the lining is desirable, but which after being stretched will return to its normal state thereby maintaining the necktie in shape.

15 A particular object of the invention is to produce a lining by cutting the fabric in suitable strips, either lengthwise or widthwise depending upon the weave. In present practice the fabric must be cut on the bias to be stretchable and also to prevent unraveling of the edges thereof. This results in a great deal of waste and the lining does not retain its elastic qualities due to gradual distortion of both the warp and weft.

25 A further object, therefore, is to produce a lining which can be cut in strips from the fabric either lengthwise or widthwise, thereby using up all of the fabric and eliminating the waste occurring in linings 30 cut on the bias, the fabric weft or warp being woven so that it will stretch in one direction either lengthwise or widthwise.

35 A further important object is to produce a lining which will stretch in either direction but not both directions in a single piece 40 of lining, that is one which is made up of a woven fabric of worsted mohair or woolen yarn or a combination of worsted and cotton or mohair and cotton, or woolen and cotton 45 yarns, in single or double ply, and one which will stretch either lengthwise or widthwise depending upon the particular weave.

50 Reference is to be had to the accompanying drawing, showing diagrammatically, a fabric constructed in accordance with my invention so far as it is practicable to do so. In this drawing 1 constitutes the loosely woven threads and 2 the closely woven threads.

In detail, the warp or weft ends of the fabric in weaving are drawn in to as wide a reed width in the loom as is feasible, that is one or the other, either the warp or the weft, depending upon whether the piece of

lining material is to stretch lengthwise or widthwise so that when it is finished and stretched it will have a tendency to spring back. It is loosely woven, so that when, during the shrinking process, the weave is 60 shrunk in close, the fabric can be subsequently stretched along its width or along its length and the weave separated, but due to its tendency to close, the fabric after being stretched will spring back.

65 After weaving the fabric is subjected to a rubberizing process, which consists in surfacing over one side of the fabric with a very thin coating of rubber or any like material. This rubberizing treatment binds 70 the weft and warp threads and at the same time allows the fabric to stretch and return to its normal position, but the binding is primarily for the purpose of preventing edge unravelling. In the linings cut on the 75 bias, no ravel occurs, but the bias cut of material entails great waste.

I weave a lining so that it can stretch either along the warp or weft depending 80 upon which is loosely woven as has been before described, and therefore the piece can be cut into lengthwise or widthwise strips. The rubberizing process prevents the unravelling of the edges of the lining as it is 85 understood that some parts of the lining are very narrow and any unravel will immediately destroy the lining at its narrow portion. My improved process therefore prevents unravelling of the edges of the tie lining.

90 It is to be understood that the fabric may be woven out of worsted, mohair, woolen yarns, or a combination of worsted and cotton, mohair and cotton or woolen and cotton 95 yarns in single or double ply.

The weft being horizontal, the weave would be stretchable along the weft only. Therefore by cutting along the width of the fabric lining I produce a lining for neckties which will be non-wrinkable and which when knotted and stretched with the tie will resume its normal woven position, when the tie is unknotted. By weaving the warp threads loosely, the material is stretchable 100 along its warp or length. By cutting along the warp I may also then have a stretchable lining having the same qualities as mentioned in connection with the weave of the weft.

105 The improved lining made in this method 110

will, therefore stretch in either of two directions only, that is along the weft or the warp, but the whole piece will be cut straight along its width or length to provide 5 lining strips and therefore the strips themselves will stretch longitudinally.

Having described my invention what I claim is:

A necktie lining fabric composed of

loosely woven normally twisted threads 10 running in one direction and relatively closer woven normally twisted threads in the other direction whereby the fabric can stretch in one direction only, the surface of the fabric being processed to prevent the 15 edges thereof from unravelling when said fabric is cut into strips.

MAX RECHER.
